ATTORNEYS.

UNITED STATES PATENT OFFICE.

JAMES W. KING, OF SAUGERTIES, NEW YORK, ASSIGNOR TO THE TISSUE COMPANY, OF SAUGERTIES, NEW YORK, A CORPORATION OF NEW YORK.

NAPKIN PACKAGE.

Application filed November 19, 1924. Serial No. 750,861.

This invention relates to napkin packages especially adapted for use in eating places.

Briefly stated, an important object of the invention is to provide a napkin holder having outwardly inclined end walls forming a gradually restricted entrance for the original placing of the napkins in the holder and also for positioning all the napkins on edge in a neat and orderly row without special 10 effort or loss of time by the operator.

A further aim is to provide a napkin package in which the triangularly folded napkins have their major portions located above the holder therefor and free from frictional or 15 pressure contact with each other and with the holder so that one or several napkins may be easily removed without disturbing the other napkins.

A further object is to provide a napkin 20 package in which the folds of the several napkins are presented upwardly to form the top of the row of napkins so that dust will be prevented from settling between the folds of the napkins.

25 A further object of the invention is to provide a napkin package which is extremely sanitary, convenient to use, and cheap to manufacture.

Other objects and advantages will be apparent during the course of the following 30 description.

In the accompanying drawing forming a part of this application and in which like numerals are employed to designate like 35 parts throughout the same,

Figure 1 is a perspective of the improved napkin package;

Fig. 2 is a vertical longitudinal sectional view through the same;

40 Fig. 3 is a horizontal sectional view taken on line 3—3 of Fig. 2;

Fig. 4 is a perspective illustrating the manner in which the napkins are removed.

In the drawing, wherein for the purpose 45 of illustration is shown a preferred embodiment of the invention, the numeral 5 generally designates the improved holder which may be of porcelain or other suitable material and which is provided with spaced parallel walls 6. Figs. 1 and 2 plainly illustrate that the side walls 6 are substantially increased in width toward their upper ends and are formed integral with outwardly inclined end walls 8. The outwardly inclined 55 end walls 8 join each other at their lower

ends as illustrated in Fig. 2 and cooperate with the side walls 6 in the formation of a gradually restricted entrance for the pointed terminal portions of a plurality of napkins 10. The napkins 10 are arranged in row formation in the more or less V-shaped pocket or chamber in the holder and are adapted to contact with the outwardly inclined walls 8 so that these walls will center the napkins without special effort or loss of time on the part of the operator. It is thus seen that the outwardly inclined walls 8 not only form a gradually restricted entrance for the original introduction of the pointed lower portions of the napkins, but also act as an accurate centering means to maintain the napkins in line with each other even during the use of the holder and after some of the napkins have been removed. By reason of this important advantage it is unnecessary for an attendant to periodically rearrange and straighten the package of napkins.

Also the major portions of the napkins are located exteriorly of the holder and are free from frictional or pressure contact with the same and with each other so that a napkin may be conveniently removed without in any way disturbing the other napkins.

Fig. 3 illustrates that the outermost napkins at each side of the package are inclined or turned outwardly away from the other napkins so as to facilitate the manual grasping of the outermost napkin or napkins. This encourages the use of the outermost napkins rather than the inner napkins of the row. That is to say, it will be obvious to a prospective user of one or more of the napkins that it would be far simpler to detach one or more of the outermost napkins than it would be to grasp a napkin in the center of the package or row. By thus encouraging the use of the outermost napkins the innermost napkins will remain untouched and in a sanitary condition.

The several napkins composing the row are folded into triangular formation and the folds are located in an approximately horizontal plane to form the top of the row. Therefore, dust cannot settle between the folds of the napkins. Also the free edges of the napkins are presented downwardly and have their major portions confined within the holder and protected thereby.

The lower portions of the side walls 6 are extended beyond the outer surfaces of the

outwardly inclined walls 8 to form a pair of supporting legs or sides and the connection between the side and end walls may be strengthened and reinforced by a plurality 5 of triangular knobs 15.

Having thus described the invention, what is claimed is:

As an article of manufacture a fixture for dispensing triangularly folded napkins and 10 comprising a molded body having side and end walls, the end walls sloping inwardly and downwardly and intersecting at their lower ends to support the side edges of triangular folded napkins to dispose the

upper portions thereof above the tops of said side walls whereby the napkins can be readily grasped and removed, the side walls following the lines of said end walls from the upper edges of the latter a substantial distance and then flaring outwardly to define 20 supporting flanges, and adjacent side and end walls being cross-sectionally thickened at aligned points adjacent the intersection thereof whereby to strengthen and reinforce the molded body at the point of greatest 25 strain.

In testimony whereof I affix my signature.

JAMES W. KING
